DESIGN.

W. C. PEET.
LEG FOR SINKS, &c.

Patented Mar. 11, 1890.

No. 19,698.

UNITED STATES PATENT OFFICE.

WILLIAM C. PEET, OF NEW YORK, N. Y., ASSIGNOR TO THE J. L. MOTTE IRON WORKS, OF SAME PLACE.

DESIGN FOR A LEG FOR SINKS, &c.

SPECIFICATION forming part of Design No. 19,698, dated March 11, 1890.

Application filed February 17, 1890. Serial No. 340,817. Term of patent 14 years.

To all whom it may concern:

Be it known that I, WILLIAM C. PEET, a citizen of the United States, residing at the city, county, and State of New York, have invented a new and original Design for the Legs of Sinks and Basins, of which the following is a specification.

I have illustrated my design by the accompanying photograph.

10 The leading features of my design are the quarter-circle or curved upper portion, the twisted column, and the claw-foot and ball. The quarter - circle or curved portion *a* is square, or nearly so, in cross-section. The 15 twisted ornamental portion *b* is circular in general contour, and the spiral convolutions are rounding or convex. The ornamental de-

sign of the leg at the bottom is a plain circular taper curved outwardly and terminating in the representation of the claw-foot *c* of a 20 bird resting on a ball *d*. A square double beaded or molded ornament *f* is at the intersection of the curved portion *a* and twisted portion *b*, and there is a circular molded ornament at *e* below the twisted ornament. 25

What I claim is—

The design for a leg for sinks, basins, &c., substantially as herein shown and described.

Signed by me this 11th day of February, A. D. 1890.

WILLIAM C. PEET.

Witnesses:

MAX GOEBEL,
HENRY MORFORD.
